UNITED STATES PATENT OFFICE.

EMILE MOLINGHEN AND JULES GAYE, OF BRUSSELS, BELGIUM.

APPARATUS FOR ACIDULATING TEXTILE AND OTHER MATERIALS.

Application filed February 5, 1926. Serial No. 36,297.

The present invention relates to the acidulation of textile and other materials, such as wool and the like, which is effected by immersing the material in a tank containing 5 the acid solution by means of a pocketed drum; the purpose of such treatment being to destroy the vegetable substances or fibers comprised in the material.

In practice, the duly-acidulated material 10 is subjected to a so-called "carbonizing" treatment which consists in evaporating, by the action of a current of dry, hot air, the water that dilutes the acid which has been intimately absorbed by the material. The 15 acid is concentrated in this way and acts to completely destroy the vegetable substances, but has little or no effect upon the wool. Sulfuric acid is generally employed; and since this acid rapidly attacks the ordinary 20 metals, excepting lead, it is important to reduce to the minimum the parts of the machine which come in contact with the acid bath.

It is particularly advisable to avoid using 25 hinged or sliding doors or similar devices for keeping the material under treatment in the pockets or compartments of the drum during the rotation of the latter; and with that end in view, the invention contemplates 30 the employment of a semi-cylindrical tank wherein the drum is arranged coaxially, the diameter of the tank being such that its cylindrical internal wall is spaced a slight 35 distance only from the drum wall and, in consequence serves as a retaining wall for the contents of the drum pockets.

The excess acid which the material absorbs on leaving the tank is eliminated by hydro-extractors connected by a tray or chute with 40 the upper part of the tank. The liquid expressed by these extractors is collected in a vessel or reservoir into which leads the suction pipe of a pump that delivers it to the container for the acidulating mixture; such 45 container being equipped with supply pipes for water and concentrated acid and also with a feed pipe for a test tube in which an acidometer is arranged.

Other features of the invention will appear 50 from the following description, and by reference to the accompanying drawings illus-

trating a construction of the machine according to the invention.

Figure 1 is a diagrammatic elevation of the machine. 55

Figure 2 shows the acidulating tank and hydroextractors in plan.

Figure 3 is a fragmental side elevation of Figure 2.

The acidulating machine according to the 60 invention essentially comprises a semi-cylindrical tank 1 adapted to receive a drum 2 divided into compartments 3 formed between partitions 3'. Referring to Figure 3, the drum is co-axial with the tank 1, so that 65 half the total number of compartments are immersed while the other half are outside the tank.

The material to be acidulated is introduced through a hopper 4 disposed above the 70 tank 1 filled with acidulating mixture to the level of the mouth of an overflow pipe 7 (Figure 1). The material in the compartments 3 of the drum 2 rotating intermittently or otherwise in the direction of the arrow 75 X (Figure 3) is first immersed in the acidulating mixture and then brought to the level of a flanged tray 27 along which it may be transferred to hydro-extractors 20 for freeing the said material from any excess of 80 acidulating solution.

The shaft 5 of the drum 2 is mounted on two suitable supports 29 and is fitted with a pulley 30 or any other convenient actuating means for rotating the drum 2 as desired. When starting the operation, the tank 1 is filled with acidulating mixture which rises to the level of the mouth of the overflow pipe 7 and is supplied to the said tank from a mixing container 9 through the 90 pipe 14. The said container is supplied with concentrated acid and diluting water through pipes 10 and 11 respectively, the acid flowing by gravity from a receptacle 15. The pipes 10 and 11 are provided with 95 valves 12 and 13 respectively.

The degree of dilution of the mixture in the mixing container 9 can be watched by means of a test tube 17 provided with an acidometer 18, the said tube being in communication with the container through a 100 draw-off pipe 16 provided with a valve 32,

and being fitted with an overflow pipe 28 leading to the overflow pipe 19 of the mixer 9.

The overflow pipes 19 and 7 open into an underground vessel or collector 21 into which open also the pipes 23 receiving the liquor from the hydro-extractors 20. This liquor is recovered by providing the pipes 23 with suitable filters 26.

Owing to this arrangement the acidulated mixture may be drawn from the collector vessel 21 by means of a suitable pump 25 and delivered to the mixing container 9 whence it is fed to the machine by gravity, as described. The collector 21 has an overflow pipe 24 leading to any suitable point of discharge.

The pipe 14 is of course provided with a regulating valve 31 for keeping the acidulating mixture in the tank 1 level with the

mouth of the pipe 7 so that the amount of liquor overflowing through the said pipe is as small as possible.

What we claim is:

A machine for acidulating textile or other materials, comprising a stationary, semi-cylindrical tank to contain acidulating liquid, and a drum rotatably mounted in said tank and having its interior partitioned into compartments; the cylindrical wall of the tank being coaxial with the axis of rotation of the drum and having its inner surface disposed so close to the partition walls of the drum as to form a retaining wall for the material contained in the compartments. 30 35

In testimony whereof we affix our signatures.

EMILE MOLINGHEN.
JULES GAYE.
